(57) **CLAIM**

The ornamental design for a detachable hitch receiver, as shown and described.

DESCRIPTION

FIG. 1 is a perspective view of a detachable hitch receiver showing our new design;

FIG. 2 is a top view thereof;

FIG. 3 is a bottom view thereof;

FIG. 4 is a front view thereof;

FIG. 5 is a rear view thereof;

FIG. 6 is a first side view thereof; and,

FIG. 7 is second side view thereof.

The broken lines in the figures are included for the purpose of illustrating portions of a detachable hitch receiver and form no part of the claimed design.
